(57) **CLAIM**

The ornamental design for a toilet flange as shown and described.

DESCRIPTION

FIG. 1 is a perspective view of a toilet flange according to a first embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a perspective view of a toilet flange according to a second embodiment of my new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a bottom perspective view thereof.

The evenly spaced broken lines depict portions of the toilet flange that form no part of the claimed design. The dot dash dot broken lines denote the boundary of the claim and form no part thereof.

1 Claim, 16 Drawing Sheets
